UNITED STATES PATENT OFFICE.

EUGENE H. FOSDICK, OF LOS ANGELES, CALIFORNIA.

BLOWPIPE.

SPECIFICATION forming part of Letter Patent No. 773,203, dated October 25, 1904.

Application filed August 31, 1903. Serial No. 171,350. (No model.)

To all whom it may concern:

Be it known that I, EUGENE H. FOSDICK, a citizen of the United States, residing at Los Angeles, in the county of Los Angeles and State of California, have invented a new and useful Blowpipe, of which the following is a specification.

This invention relates to blowpipes; and one object of the invention is to provide a blowpipe by which flames of various sizes are almost instantaneously obtained by a simple adjustment of the device.

Another object is to provide a blowpipe which may be readily adjusted to direct the flame as desired.

Other objects of the invention are to produce a device of the character described which is extremely simple in construction, effective in operation, and may be easily controlled.

Heretofore it has been usual to employ independent burners for each size of flame desired. Sometimes detachable nozzles of different sizes are provided with a burner, so as to have at command the desired size of flame.

The first is objectionable because of the inconvenience of having several burners on the bench, which takes up room, and the second is objectionable because to change the size of the flame necessitates turning out the fire, re-

moving the outer gas-nozzle sleeve, taking off the air-jet, and replacing by the one desired to give a suitable flame. The outer gas-nozzle sleeve has then to be replaced and the fire ignited.

In the present invention the burner is equal in capacity to several burners, but is compact in form and may be readily manipulated, there being three blowpipes on one base.

The invention has manifold applications in general laboratory work, such as ignitions, for brazing, and for glass-blowing.

The accompanying drawings illustrate the invention, and referring to the same, Figure I is a side elevation of the blowpipe. Fig. II is a plan view of the blowpipe. Fig. III is a front elevation of the blowpipe. Fig. IV is a rear elevation of the blowpipe. Fig. V is a section on line V V, Fig. III. Fig. VI is a section on line VI VI, Fig. III. Fig. VII is a section on line VII VII, Fig. III. Fig.

VIII is a view of the rear face of the segmental nozzle-carrier. Fig. IX is a face view of the segmental supporting-plate. Fig. X is a view looking at the bottom wall of a nozzle.

Briefly, the present embodiment of the invention comprises a nozzle-carrier equipped with nozzles of various sizes, the nozzle-carrier being movable to bring a desired nozzle into communication with a supply-feeder.

The invention further comprises means whereby the nozzle-carrier may be adjusted so as to direct the flame from a nozzle in the desired direction.

1 designates a base from which a standard 2 projects.

3 is a segmental feeder-plate, the lower end of which is provided with a knuckle 4, arranged transversely thereof and which is held in close contact with a similar knuckle 5, carried by the standard 2, by means of a screw 6, which passes through both knuckles. The screw 6 may be provided with a finger-lever 7 for operating the same and loosening or tightening the screw to clamp the two knuckles together, so that the feeder-plate may be adjusted to the proper pitch or inclination relatively to the base 1.

A segmental nozzle-carrier 8 is swiveled on a bolt 9, which is mounted in the feeder-plate 3, there being a washer 10, which lies next to the feeder-plate, and a coil-spring 11, interposed between the washer and the nut on the bolt 9. The nozzle-carrier 8 lies flatly against the feeder-plate 3, and the contacting faces of the feeder-plate 3 and nozzle-carrier 8 are perfectly smooth. The strength of the spring 11 is sufficient to hold the contacting faces tightly enough together to prevent any escape of gas or air, although the spring will allow the nozzle-carrier to be shifted on the feeder-plate 3.

The feeder-plate 3 is provided with an air-passage 12 and a gas-passage 13, there being an air-cock 14 screwed to the passage 12 and a gas-cock 15 screwed into the passage 13.

A pilot-light is maintained from a jet-pipe 16, which projects from a cock 17, which is connected by pipe 18 with the gas-cock 15.

In the present embodiment I have shown the nozzle-carrier as constructed to support

three burner-nozzles, (designated 19, 20, and 21, respectively.) These nozzles may be of any desired form; but in my preferred construction each burner-nozzle comprises an outer shell 22, which is tapered at one end to fit snugly within a taper hole in the nozzle-carrier. Within the shell 22 is an air-tube 23, preferably of glass to reduce friction, which is supported concentrically within the shell at

- 10 the rear by a bushing 24, which may preferably be of soft rubber, so as to form a tight non-leakable joint. The forward part of the air-tube 23 may be supported by means of centering-screws 25. The centering-screws 25
- 15 may preferably be arranged equidistant in the shell 22 and are of a size sufficiently small to not impede the passage of gas to an appreciable extent. The air-tube terminates short of the end of the shell 22, which thereby forms
- 20 a combined mixing-tube and burner-nozzle of the usual construction. The shell 22 near its inner end on its lower side is provided with an orifice 26, which registers with an air-passage in the nozzle-carrier.

25 Referring to Fig. VIII, it will be seen that in the present embodiment the nozzle-carrier is provided with three gas-passages 27, 28, and 29, respectively. These gas-passages are formed radially, as shown, and have horizontal galleries 30, 31, and 32, respectively. Either of the gas-passages is adapted to be brought into communication with the gas-passage 13 in the feeder-plate 3. The nozzle-carrier 8 is provided with a handle 33, by which it may 35 be moved to bring either of the nozzles into communication with the gas and air passages 13 and 12 in the feeder-plate 3.

30 The nozzle-carrier 8 may be yieldingly locked in position when a nozzle is in register with the passages 12 and 13 by means of a spring locking-plate 34, which has a slight projection 35, adapted to engage in depressions 36, 37, and 38, sunk in the upper rim of the nozzle-carrier 8.

40 45 If a small needle-flame is desired, the operator throws the nozzle-carrier over to bring the nozzle 19 to the center of the feeder-plate 3, the plate 34 locking and positioning it automatically. When the nozzle-carrier is in this position, the gas-passage 27 is in communication with the gas-passage 13 and the air-tube 23 of the nozzle 19 is in communication with the air-passage 12. The cocks 14 and 15 are adjusted to admit the requisite respective 50 amounts of air and gas to the nozzle, according to the judgment of the operator. If the next larger flame is desired, the operator moves the nozzle-carrier into the position shown in Fig. II to bring the middle nozzle 55 60 65 20 into communication with the air and gas passages 12 and 13, while if the largest flame is desired the operator moves the nozzle-carrier to bring the nozzle 21 into communication with the air and gas passages 12 and 13.

65 The pilot-light 16 may be kept alight con-

stantly, so that in working the burner the operator has at his immediate command a flame of the desired size and quality, either flame being obtained instantly by throwing the nozzle-carrier into the requisite position, the pilot-light 16 instantly igniting the gas which issues from the centered nozzle as soon as the nozzle is in register with the air and gas passages.

70 The valuable feature of having at instant 75 command a flame of the desired size is supplemented by the adjustability of the burner to direct the flame to the particular angle desired. The adjustment of direction of flame is made very quickly by loosening the screw 80 6 by means of the handle 7, tilting the feeder-plate, nozzle-carrier, and attached parts to the desired angle as one piece, and then clamping the screw 6 by a slight turn of the lever.

85 While I have shown and described the preferred embodiment of my burner, in which the nozzle-carrier is constructed to carry three nozzles, I do not limit myself to the number of nozzles supported by the carrier, for the nozzle-carrier could be constructed to support a 90 less number than three, and it could also be constructed to carry more nozzles than three. Neither do I limit myself to the particular shape of the nozzle-carrier, feeder-plate, or other parts, as it is evident that the construction of the 95 same could be varied without departing from the spirit of my invention. Neither do I limit myself to mounting the nozzle pivotally or arranging the nozzles at points concentric with the pivot. Furthermore, a blowpipe embodying in its construction a plurality of nozzles, means for supporting the same, a feeding means combined therewith, one of the two latter elements being movable relatively to the other for producing a discharge of the combustion matter through the desired nozzle, would lie within the scope of my invention. Neither do I limit myself to the precise construction for adjusting the flame to the angle desired, as any means for adjusting the nozzle 100 relative to the base may be employed.

105 110 What I claim is—

115 120 1. A flat support provided with means for feeding combustible material, a flat nozzle-carrier mounted on the support and provided with a plurality of nozzles, mechanism for causing said feeding means and either one of the nozzles to register, and a base for adjustably holding said support and carrier.

125 130 2. A nozzle-carrier, a plurality of nozzles thereon, said nozzles being parallel with each other and extending substantially at right angles from the carrier, a feeding element, the nozzle-carrier being movably mounted relatively to the feeding element whereby the desired nozzles may be brought into working communication with the feeding elements, and a base adjustably supporting the foregoing elements.

130 3. A nozzle-carrier, a plurality of nozzles

projecting therefrom, the rear end of each of which is provided with two openings, a support for the carrier provided with two fuel-openings, means for causing the rear openings of either one of the nozzles to register respectively with the fuel-openings, and a base for adjustably supporting said parts.

4. A plurality of nozzles, means for supporting the same, feeding means combined therewith and having a gas-passage and an air-passage, the second and third elements being movable one relatively to the other for placing the gas and air passages in communication with a nozzle.

15 5. A plurality of nozzles, means for supporting the same, feeding means combined therewith, one of the two latter elements being movable relatively to the other for producing a discharge of the combustion matter through the desired nozzle, and means for locking the nozzle-supporting means in position.

6. A plurality of nozzles, means for supporting the same, feeding means combined therewith, one of the two latter elements being movable relatively to the other for producing a discharge of the combustion matter through the desired nozzle, and means for detachably locking the nozzle-supporting means in position.

30 7. A base, a flat feeder - plate pivotally mounted thereon to move in a plane at right angles to its own flat face, a nozzle-carrier movably mounted on said face, and a plurality of nozzles on the carrier.

8. A base, a flat feeder - plate pivotally mounted thereon to move in a plane at right angles to its own flat face and provided with means for feeding combustible material, and 40 a flat nozzle-carrier pivotally mounted on the plate and provided with nozzles, each projecting at an angle therefrom and in position to be moved into and out of register with said feeding means.

45 9. A feeder-plate, a nozzle-carrier pivotally mounted thereon, and a plurality of nozzles carried by the nozzle-carrier, the feeder-plate having a gas-passage and an air-passage, the nozzles being mounted at points an equal distance from the pivot of the nozzle-carrier.

10. A feeder-plate having a gas-passage and an air-passage, a nozzle-carrier pivoted to the feeder-plate and having a series of air-passages and gas-passages, and a series of nozzles 55 on the nozzle-carrier, each nozzle communicating with its respective air and gas passages.

11. A base, a flat plate mounted thereon and provided with means for feeding combustible material, a flat nozzle-carrier pivotally mounted on the plate, and a plurality of nozzles arranged in the arc of a circle on the carrier in position to be moved into and out of register with said feeding means.

60 12. A base having a knuckle, a feeder-plate having a knuckle, a bolt through the two

knuckles, a finger-lever on the bolt, and a nozzle-carrier pivoted to the feeder-plate at right angles to said bolt.

13. A feeder-plate, a nozzle-carrier pivoted thereto, means for resiliently holding the nozzle-carrier against the feeder-plate, and a base adjustably supporting said elements.

70 14. A feeder-plate, a nozzle-carrier, a bolt through said feeder-plate and nozzle-carrier, a coil-spring held against the feeder-plate by the nut, and a base adjustably supporting said elements.

15. A base, a feeder-plate adjustable thereon, a nozzle-carrier pivotally mounted on the feeder-plate, a spring locking-plate on the 80 feeder-plate having a projection, the nozzle-carrier having a series of depressions adapted to receive the projection.

16. A base, a feeder-plate adjustable thereon, a nozzle-carrier pivoted to the feeder-plate, means for resiliently holding the nozzle-carrier in flat contact with the feeder-plate, a hand-lever on the nozzle-carrier for shifting the same, and a base adjustably supporting said elements.

85 17. A base, a feeder-plate adjustable thereon, a nozzle-plate pivoted to the feeder-plate and having radial gas-passages with transverse galleries, the nozzle-plate also having air-passages, and taper holes, a series of nozzles having tapered ends fitting in the holes, each nozzle communicating with an air-passage and a gas-passage.

90 18. A base, a feeder-plate adjustable thereon and having an air-passage and a gas-passage, a nozzle-carrier pivoted to the feeder-plate, a plurality of nozzles on the nozzle-carrier, and a gas-cock for the gas-passage, an air-cock for the air-passage.

100 19. A base, a feeder-plate adjustable thereon and having an air-passage and a gas-passage, a nozzle-carrier pivoted to the feeder-plate, a plurality of nozzles on the nozzle-carrier, and a gas-cock for the gas-passage, an air-cock for the air-passage, a jet-pipe connected with the gas-cock and extended forward with its end adjacent the end of a positioned nozzle.

105 20. A base, a feeder-plate adjustable thereon and having an air-passage and a gas-passage, a nozzle-carrier pivoted to the feeder-plate, a plurality of nozzles on the nozzle-carrier, and a gas-cock for the gas-passage, an air-cock for the air-passage, a jet-pipe connected with the gas-cock and extended forward with its end adjacent the end of a positioned nozzle, and a cock for the jet-pipe.

115 21. A base, two members adjustably mounted thereon, one of which is movable relatively to the others and one of which is provided with means for feeding a mixed fuel and the other with a plurality of burner-nozzles, means for varying the mixture and positively regulating the amount of each kind independently of the other, and means for moving

120 125 130

either one of said nozzles into connection with the fuel-supply.

22. A base, two members adjustably mounted thereon one of which is movable relatively 5 to the other and one of which is provided with means for feeding mixed fuel, a plurality of burner-nozzles of different sizes on the other member, each of which is adapted to be moved into and out of register with the 10 feeding means, and means for regulating the supply of each kind of fuel independently of the other.

23. A base, two members adjustably mounted thereon, one of which is movable relatively 15 to the other, and one of which is provided with two openings, means for controlling each of said openings independently of the other, the other member being provided with a plurality of openings one end of each of which 20 is double and adapted to be moved into or out of register with the two openings in the other member, and a combined mixing and burner-nozzle projecting from the outer end of each of said last-mentioned openings, said nozzles 25 being of different sizes.

24. A base, a member thereon, a plurality

of different-sized nozzles projecting from said member, a tube in each of said nozzles, the outer end of each of which terminates at a distance from the outer end of its respective 3 nozzle, adjustable means for supporting the outer end of each tube and means for variably feeding a mixed fuel to either one of said nozzles independently of the others.

25. A base, a member thereon, a plurality 35 of different-sized nozzles projecting from said member, tubes mounted axially within the nozzles respectively, the outer end of each of which tubes terminates at a distance from the outer end of its nozzle, soft annular packing 40 around the inner ends of the tubes respectively, and means for variably feeding a mixed fuel to the tube and nozzle.

In testimony whereof I have signed my name to this specification, in the presence of two sub- 45 scribing witnesses, at Los Angeles, in the county of Los Angeles and State of California, this 22d day of August, 1903.
